(57) **CLAIM**

The ornamental design for a shovel, as shown and described.

DESCRIPTION

FIG. 1 is a front, top, left side perspective view of a shovel.

FIG. 2 is a top view of the shovel of FIG. 1.

FIG. 3 is a bottom view of the shovel.

FIG. 4 is a right-side view of shovel.

FIG. 5 is a left-side view of the shovel.

FIG. 6 is a rear view of the shovel; and,

FIG. 7 is a front view of the shovel.

The broken lines showing of the symbolic break forms no part of the claims design.

The broken lines in the drawings illustrate portions of the shovel and form no part of the claimed design.

1 Claim, 5 Drawing Sheets(56)
